UNITED STATES PATENT OFFICE.

LOUIS ROSSI, OF NEW YORK, N. Y., ASSIGNOR OF ONE-HALF TO FRANK A. SANFORD,
OF NEW YORK, N. Y.

DISPENSING DEVICE.

Application filed May 17, 1927. Serial No. 192,059.

This invention relates to dispensing devices and has particular reference to a device which is especially designed for dispensing toothpicks although it is to be understood that the same is not necessarily limited to this use.

The invention aims to provide a means for eliminating the unsanitary practice of placing toothpicks in restaurants and other public eating places, in an open container where the patrons inadvertently handle toothpicks other than the ones which they take for their own use. This practice is also open to the objection that the patrons take a greater quantity of toothpicks than necessary, thereby subjecting the proprietor to an unwarranted expense.

One of the principal objects of the present invention is to provide a dispensing device of the character set forth which includes a positive discharging means which insures the dispensing of a predetermined number of the articles to be dispensed without failure.

A further object of the invention resides in the provision of means for agitating the articles in the hopper or container therefor, to insure the positive feeding of the article to the discharging means.

Other objects reside in the comparative simplicity of construction of the device, the economy with which the same may be produced, and the general efficiency derived therefrom.

With the above recited and other objects in view, reference is had to the following description and accompanying drawings in which there is exhibited one example or embodiment of the invention, while the appended claims define the actual scope of the invention.

In the drawings—

Figure 1 is a perspective view of the dispensing device;

Fig. 2 is a vertical sectional view thereof taken approximately on the line 2—2 of Fig. 1 and illustrating the parts in discharging position;

Fig. 3 is a similar view with the parts shown in feeding position;

Fig. 4 is a transverse sectional view taken approximately on the line 4—4 of Fig. 2.

Referring to the drawings by characters of reference, 10 designates a supporting frame which includes a pair of laterally spaced side plates 11 between which a hopper 12 is

positioned, the hopper having slotted ears 13 through which and the side plates 11 of the frame, bolts 14 extend for adjustably associating the hopper with the frame. The side plates 11 of the frame are provided on the inner faces thereof, with inwardly projecting longitudinal upper and lower guide flanges 15 and 16, said guide flanges being preferably inclined upwardly from the front to the rear of the frame. The hopper 12 is provided with an enlarged upper open end and with front and rear downwardly converging walls 17 and 18 defining at the lower end a restricted discharge opening 19. A valve element preferably in the nature of a plate 20, is mounted between the guides 15 and 16 of each side frame element 11 for fore-and-aft sliding movement. The slide-able valve plate 20 includes a section 21 which is hingedly connected by a hinge 22 to the forward end of the main section 21 for downward swinging movement. The lower guide flanges 16 are provided with down-turned forward ends 23 to permit of the downward swinging movement of the section 21 when the valve plate is moved to the forward limit of its movement. The sections 20 and 21 at their juncture have rabbeted upper corners 24 and 25 which define together when the sections are in longitudinal alignment, a receiving pocket or groove registrable with the discharge opening 19 of the hopper when the valve sections are moved in a rearward direction to the limit of their movement, whereby the articles in the hopper to be dispensed are received from the hopper through the discharge opening or end. While the section 21 may swing down gravitationally, a coiled contractile spring 26 has its opposite ends respectively connected to the under sides of the sections 20 and 21 to insure the downward swinging movement of the section 21. The under side of the main section 20 of the valve plate has depending therefrom a pin 27 to which a pair of coiled contractile springs 28 are connected at one end, the opposite ends being connected to pins 29 depending from the forward portion of the frame 10. The springs 28 function to normally move the slide valve in a forward direction. The hopper is adjusted so that its lower discharge end is slightly spaced directly above the upper surface of the valve plate whereby the upper surface of the valve plate in the normal position,

closes the discharge opening 19 of the hopper. A substantially U-shaped lever 30 has its side arms 31 fulcrumed at 32 to the side frame elements 11, and the light portion 33 of said lever is formed with a shaft 34 upon which a roller 35 is mounted, the roller engaging the depending pin 27. The side arms of the lever have their upper ends formed with forwardly extending arcuate terminals 36, which are joined by a cross portion 37. The cross portion has projecting outwardly from and secured to the medial portion, a manipulating lever 38, formed with a finger key 39. The roller engaging with the pin 27 is adapted upon depression of the finger key 39 to move the valve plate rearwardly. The initial rearward movement of the valve plate causes the section 21 riding up the downturned ends 23 of the lower guides 16, to be swung to a position in longitudinal alignment with the main body portion 20 so that the rabbeted corners 24 and 25 define a receiving pocket. Continued rearward movement is arrested by the engagement of the pin 27 with the shoulder 40 defined by the frame 10, at which point the receiving pocket is disposed in registry with the hopper outlet opening 19 so that one or a predetermined number, in the present instance two, of the toothpicks or other articles A which are to be vended, may gravitate into the receiving pocket. When the key is released, it is obvious that the springs 29 will project the valve plate forwardly until the pin contacts with the stop element 41 also defined by the frame 10, at which point the section 21 will have moved over the downturned forward ends 23 of the lower guides 16 and by gravity and the action of the spring 26 will have been swung to a substantially right-angular position opening the pocket and discharging the toothpicks or articles A therefrom. The device or machine will preferably include a base 42 to which the frame 10 is attached and a housing or casing 43 carried by the base for enclosing the frame, hopper and mechanism. The housing will have a removable cover 44 and will further be provided with a chute or trough 45 in the lower portion of its flange wall, for receiving and gravitationally disposing the toothpicks or articles A externally of the housing when they are discharged from the valve plate and received thereby. The front wall of the housing 43 will also be provided with a vertical slot 54 through which the manipulating lever 38 extends and from which the finger key is exposed.

In order to provide means for facilitating the feeding and preventing clogging of the toothpicks or articles A in the hopper, an agitator plate 46 is mounted within the hopper preferably to slide on the front wall 17.

The said agitator plate is provided with a

serrated inner face 47 and is suitably connected with a cross bar 48 disposed exteriorly of the front wall 17 by means of connecting pins or rivets 49 extending through slots 50 in the front wall 17. The cross bar 48 has journaled on its opposite ends, rollers 51 which are engaged by the under cam faces 52 of the arcuate terminals 36 of the side arms 31 of the U-shaped lever 30. In operation, downward and forward movement of the terminals 36 causes the under cam surfaces 52 to exert a downward pressure on the agitator plate 46. Four contractile springs 53 are connected respectively at their opposite ends to the cross bar 48 and the upper end of the hopper for moving the agitator plate 46 upwardly when the finger grip and manipulating lever 48 are released.

What is claimed is:

1. A dispensing device including a hopper, a valve element having a receiving pocket registrable with the discharge end of the hopper upon movement of the valve element in one direction for receiving from the hopper through the discharge end, an article to be vended, and means co-operating with the valve element upon movement in an opposite direction for effecting a wide opening of the pocket to cause a discharge of the contents. 85

2. A dispensing device including a hopper, a valve element having a receiving pocket registrable with the discharge end of the hopper upon movement of the valve element in one direction for receiving from the hopper through the discharge end, an article to be vended, and means co-operating with the valve element upon movement in an opposite direction for effecting a wide opening of the pocket to cause a discharge of the contents; 105 in combination with means in the hopper for agitating and positively feeding articles through the discharge end when the valve element pocket registers therewith. 105

3. A dispensing device including a hopper having a discharge end, a valve element having sections defining a receiving pocket registrable with said discharge end upon movement of the valve element in one direction for receiving from the hopper through the discharge end an article to be vended, and means co-operating with the valve pocket-defining sections upon movement of the valve element in an opposite direction, for effecting relative separation of said sections to open the pocket widely for causing a positive discharge of the contents. 115

4. A dispensing device including a hopper having a discharge end, a slidable valve plate having hingedly connected sections defining a receiving pocket registrable with said discharge end upon movement of the valve element in one direction for receiving from the hopper through the discharge end an article to be vended, and means co-oper- 125

ating with the valve pocket-defining sections upon movement of the valve element in an opposite direction, for effecting relative separation of said sections to open the pocket 5 widely for causing a gravitational discharge of the contents.

5. A dispensing device including a hopper having a lower discharge end, a slide plate having an end section hinged for downward 10 swinging movement, a guide over which the plate is slidable, said guide having downturned ends, the hingedly connected ends of the hinged section and slide plate having rabbeted corners defining when the same 15 are in alinement and under the discharge end of the hopper, a receiving pocket for the reception of a predetermined number of articles from the hopper and adapted when the slide plate is shifted to the downturned end of 20 the guide to separate the rabbeted corners for opening the pocket to positively effect the discharge of the articles contained in said pocket.

6. A dispensing device including a hopper having a lower discharge end, a slide plate having an end section hinged for downward swinging movement, a guide over which the plate is slidable, said guide having downturned ends, the hingedly connected ends of the hinged section and slide plate having rabbeted corners defining when the same are 25 in alinement and under the discharge end of the hopper, a receiving pocket for the reception of a predetermined number of articles from the hopper and adapted when the slide plate is shifted to the downturned end of the guide to separate the rabbeted corners for opening the pocket to positively effect the discharge of the articles contained in said pocket, and an agitator plate slidably mounted within and on one of the walls of the hopper for positively feeding the articles 30 through the discharge end of the hopper into the slide plate pocket.

7. A dispensing device including a hopper having a lower discharge end, a slide plate having an end section hinged for downward swinging movement, a guide over which the plate is slidable, said guide having downturned ends, the hingedly connected ends of the hinged sections and slide plate having rabbeted corners defining when the same are 45 in alinement and under the discharge end of the hopper, a receiving pocket for the reception of a predetermined number of articles 50 from the hopper and adapted when the slide plate is shifted to the downturned end of the guide to separate the rabbeted corners for opening the pocket to positively effect the discharge of the articles contained in 55 said pocket, an agitator plate slidably mounted within and on one of the walls of the hopper for positively feeding the articles through the discharge end of the hopper into the slide plate pocket, and a common actuating means for the slide plate and agitator plate.

8. In a dispensing device including a hopper having a lower discharge end, a feed plate underlying said discharge end and normally closing the same, said feed plate having a groove adapted upon shifting of the plate to register with the hopper at the discharge end, to receive from the hopper an article to be vended, the said feed plate being 70 split along a line coincident with a groove to provide a plate section, a hinged connection between said plate section and the remainder of the feed plate permitting downward swinging movement of said section, and a guide for said plate having a downturned end coacting with said hinged section to permit downward swinging movement thereof for effecting a wide opening of the groove to insure a positive discharge of the 75 articles received from the hopper.
